DESIGN FOR A DRAINBOARD FOR A SINK

George E. Whitlock, Warren, Ohio, assignor to
Mullins Manufacturing Corporation, Salem,
Ohio, a corporation of New York

Application August 9, 1945, Serial No. 121,336

Term of patent 7 years

(CL. D4—2)

To all whom it may concern:

Be it known that I, George E. Whitlock, a citizen of the United States, residing at Warren, in the county of Trumbull and State of Ohio, have invented a new, original, and ornamental Design for a Drainboard for a Sink, of which the following is a specification, reference being had to the accompanying drawing, forming part thereof.

Figure 1 is a perspective view of a drainboard for a sink showing my new design;

Fig. 2 is a top plan view thereof; and

Fig. 3 is a section taken on the line 3—3, Fig. 2.

I claim:

The ornamental design for a drainboard for a sink, substantially as shown.

GEORGE E. WHITLOCK.
